UNITED STATES PATENT OFFICE.

GEORGE MULLIGAN, OF TAUNTON, MASSACHUSETTS, ASSIGNOR OF ONE-HALF TO ALBERT S. MITCHELL, OF SAME PLACE.

CARPET-STRETCHER.

SPECIFICATION forming part of Letters Patent No. 273,130, dated February 27, 1883.

Application filed January 2, 1883. (No model.)

To all whom it may concern:

Be it known that I, GEORGE MULLIGAN, of Taunton, in the county of Bristol and State of Massachusetts, have invented certain new and useful Improvements in Carpet - Stretchers; and I do hereby declare the following to be a full, clear, and exact description of the same, reference being had to the accompanying drawings, forming part of this specification, in 5 to which—

Figure 1 is a side elevation of my invention, showing the manner of using it; Fig. 2, a top plan view of the same. Fig. 3 is a bottom plan view of the toothed head; Fig. 4, a sectional view taken on the line *x x* of Fig. 3.

Similar letters of reference in the several figures denote the same parts.

My invention consists of an improved carpet-stretcher constructed and adapted for operation substantially as I will now proceed to describe.

Referring to the accompanying drawings, A B represent two arms, jointed together by a cross-bolt, *a*, upon which works a set-nut, *b*. To the arm A is connected a cross piece or head, C, suitable brace-rods, *c*, extending from the arm to the head near its ends, as shown, for strengthening the connection between the parts. Upon the under face of the head C is secured a plate, 25 D, preferably of metal, having two or more openings, *d*, through which project groups of sharp forwardly-inclined prongs or teeth *e*, connected preferably to a flexible backing, E, interposed between the head and the plate D, as clearly shown in Fig. 4. The outer end of 30 the arm B is perforated for the passage of a bolt, *f*, and from this bolt depend links F, which are perforated at their lower ends for the passage of a bolt, G.

40 H represents a bar having a series of holes, *h*, extending laterally through it at intervals throughout its entire length, and carrying at one end an end piece, I. The cross-bolt G is adapted to pass through the links F and 45 through one of the several holes *h*, and to form, in connection with the links, an adjustable pivotal connection between the arm B and the bar H.

In putting down a carpet one edge of the 50 carpet is tacked near the base-board at one side of the room, and the carpet is spread out

and drawn with the hand, as near as may be, to the opposite side of the room. The end piece, I, of the bar H of the stretcher is then placed against the base-board at the tacked edge of the carpet, and the cross-bolt G is adjusted through the links and through one of the holes *h* of the bar H, with the head C bearing the prongs or teeth engaged with the carpet near its edge at the opposite side of the room. The 55 operator then bears down upon the joint of the arms A B until the arms are sufficiently depressed and extended to cause the toothed head to stretch the carpet and bring its edge to the opposite base-board, and when this is 60 accomplished he tightens up the nut *b*, thus clamping the arms A B securely in their adjusted position, and enabling him, with hammer and tacks, to secure the edge of the carpet. This operation is repeated until the carpet is secured all around.

The adjustability of the cross-bolt G in the various holes of the bar H gives the stretcher a wide range of action and enables it to be employed effectively in rooms of varying lengths, 75 while the connection of the arms A B with each other and with the bar H through the adjustable pivoted link F renders the whole device easily carried, as an entirety, from place to place, and without disturbing the relations 80 of the parts.

Having thus described my invention, I claim as new—

1. The herein-described carpet stretcher, consisting of the jointed arms, one of which carries the toothed head, the bar having the end piece and the series of adjusting-holes, the links and bolts connecting one of the arms with the adjusting-bar, and the cross-bolt and set-nut for rigidly clamping and holding the 85 arms in the position to which they are adjusted, the whole arranged and operating substantially as described.

2. The combination, with the head, of the plate secured to its under side, and having the opening and the forwardly-inclined prongs or teeth, and its flexible backing between the plate and the head, substantially as described.

GEORGE MULLIGAN.
